UNITED STATES PATENT OFFICE.

WORDEN P. PENN, OF BELLEVILLE, ILLINOIS.

IMPROVEMENT IN SEEDING-MACHINES.

Specification forming part of Letters Patent No. 31,088, dated January 8, 1861.

To all whom it may concern:

Be it known that I, WORDEN P. PENN, of Belleville, in the county of St. Clair and State of Illinois, have invented a new and useful Improvement in Seeding-Machines; and I do hereby declare that the following is a full, clear, and exact description of the same, reference being had to the annexed drawings, making part of this specification, in which—

Figure 1 is a top view of my improved machine; Fig. 2, a transverse section through the same on the line A'; Fig. 3, an inverted view of the hopper-box of the said machine. Fig. 4 is a longitudinal section taken on the line B', and Fig. 5 a longitudinal section taken on the line C'.

This invention, being an improvement in the seeding-machine, extends only to a part thereof, the remaining part of the machine being made in the usual manner. I shall therefore confine this description to so much of the machine as my invention extends to, and which I conceive to be novel. The rest of the machine being common will need no particular description.

The first point of novelty composing this improvement consists in the arrangement and combination of a rotating or other colter, B C, with the drag-bar A, for the purpose of cutting the course of the flukes B'', that the said flukes may pass through firm or trashy ground with greater ease and with less liability to choke or clog.

The second point of novelty which constitutes a part of this invention consists in combining with the feed-wheels E small pins a a, for the purpose of stirring the seed and clearing away the straws and dirt, so as to insure a

continuous flow of seed through the hopper. These pins may be fixed either in the angle of the arms of the feed-wheels, or they may be made short and fixed in the ends of the arms of the said wheels, performing the same function in either case.

The third point of novelty which constitutes a part of this my invention consists in arranging over the feed-wheels, and in combination therewith, a fender, F, a little over and slightly inclined to one side of the wheel, for the purpose of equalizing the pressure of the grain to the discharging-opening. This improvement applies particularly to wheat, which is liable to choke the passage.

The fourth point of novelty which constitutes a part of my invention consists in connecting the valve-bar P to the chain-bar R by means of an adjustable connecting-rod, v. The object of this arrangement is to enable the operator to open and close the valves by the same motion that raises and lowers the flukes without interfering with the proper motion of either. This object is effected by means of the slip-joint e in the said connecting-rod, whereby the said valves are regulated in the amount of their throw.

Having thus described the construction and operation of my invention, what I claim as my invention, and desire to secure by Letters Patent, is—

The joint arrangement of the cleaning-pins a a a, the feeding-wheel E, the fender F, and revolving colter C, in the manner described.

W. P. PENN.
